TOY ROCKET LAUNCHER

Albert M. Steiner, Cincinnati, Ohio, assignor to Bromo-Mint Company, Inc., Cincinnati, Ohio, a corporation of Ohio

Application November 29, 1955, Serial No. 39,081

Term of patent 14 years

(Cl. D34—15)

I claim:

The ornamental design for a toy rocket launcher, substantially as shown.
